[57] CLAIM

The ornamental design for a portfolio, as shown and described.

DESCRIPTION

FIG. 1 is a front perspective view of the portfolio showing my new design;

FIG. 2 is a rear perspective view thereof;

FIG. 3 is a front perspective view thereof, in an opened position, shown with the inside flap to the right; and FIG. 4 is a front perspective view thereof, in an opened position, shown with the inside flap to the left.

The broken lines shown in FIG. 1-4 represent conventional stitching.

FIG. 3.

III-4.
